UNITED STATES PATENT OFFICE

WILLIAM D. ANTRIM, OF GLOUCESTER, NEW JERSEY, ASSIGNOR TO ROBERTS & MANDER
STOVE COMPANY, OF PHILADELPHIA, PENNSYLVANIA, A CORPORATION OF PENN-
SYLVANIA

OVEN DOOR SPRING FOR RANGES

Application filed January 31, 1930. Serial No. 424,955.

My invention relates to improvements in springs for oven doors of either gas, electric or coal ranges.

The object of my invention is to provide a spring which can be readily applied to the frame of the range.

A further object of the invention is to mount the springs on a detachable bar which can be readily secured to the frame of the range. Springs of this type are for the purpose of closing the oven door when it is partly raised or to retain the door in its full open position. This object I attain in the following manner, reference being had to the accompanying drawings, in which:

Fig. 1 is a rear view of a portion of an open frame of a gas stove, showing the oven door closed and illustrating my improved spring arrangement and the detachable supporting bar for the springs;

Fig. 2 is a sectional view on the line 2—2, Fig. 1;

Fig. 3 is a sectional view on the line 3—3, Fig. 1;

Fig. 4 is a side view of the detachable bar and the springs mounted thereon;

Fig. 5 is a plan view of the detachable bar with the springs removed;

Fig. 6 is a perspective view of the detachable bar;

Fig. 7 is a rear view similar to a portion of Fig. 1, showing the door in the open position; and

Fig. 8 is a view illustrating a modification of the invention.

1 is the frame of the oven and broiler portion of a gas range in the present instance. The lower opening 2 is the broiler opening, and the upper opening 3 is the oven opening, but these parts may be reversed without departing from the essential features of the invention. 4 is a cross-bar which extends from one side member of the frame to the other and separates the oven opening from the broiler opening. 5 is the oven door, having

hinge projections 6 of the ordinary type which rock on depressed bearings 7 of the cross-bar of the oven frame. It will be understood that where the door is provided for the broiler as well as for the oven, the hinge construction and the spring arrangement which are described hereinafter are duplicated at the broiler opening, and where other doors are provided for the gas or other range, this spring arrangement can be used without departing from the essential features of the invention.

Each hinge projection 6 of the door is extended as at 8 and in each of these extensions are sockets 9 for the end 10 of a coil-spring 11. One of the springs is a right-hand spring and the other is a left-hand spring as shown in Fig. 1. Each coil-spring is mounted on a post 12 projecting from a detachable bar 13, as shown in Figs. 1 and 2. The posts in some instances may be made integral with the cross-bar 4a of the frame of the stove, as shown in Fig. 7. Each post 12 is slotted at 14 and the slot is offset at 15, so that when one end 16 of the coil-spring is inserted in the slot, it will be engaged by the offset portion and held onto the post. The post is conical in shape and the spring conforms to the shape of the post.

The outer end 10 of each spring 11 is preferably bent as shown, so that when the door is in the open position, as in Fig. 7, the bent portion 10 will rest against the wall of the socket 9 of the hinge projection, and the spring will press against the edge of the spring projection, creating a certain amount of friction which will aid in keeping the door in the open position until it is raised past a given point.

The detachable bar 13 is held in place at the back of the cross-bar 4 by a screw bolt 17, which passes through a lug 18 projecting from the door frame and through a projecting portion 19 of the bar. The bar rests in a recess 20 in the door frame, the upper end

of the bar fitting against the flange 21 of the frame, so that when the screw bolt 17 is drawn tight, there is a snug fit between the bar and the frame.

5. The above arrangement takes the place of the flat spring plate heretofore used. The coil-springs shown are more flexible than the flat-springs and are not so liable to break, and the detachable bar with the springs mounted thereon can be readily placed in position or removed from the frame.

10. The modification shown in Fig. 7 can be readily used on the broiler section of the range but it is difficult to mount the springs on the posts forming part of the frame at the oven opening and while the construction shown in Fig. 7 can be used, I prefer the construction shown in Fig. 1.

I claim:—

20. 1. The combination in an oven, of a frame; a door pivotally mounted thereon; a hinge projection on the door having an extension in which is a socket; a post at the back to the frame; and a coil spring on the post, one end of the spring being secured to the post and the other extending into the socket on the hinge projection of the door.

25. 2. The combination in a range frame; a door mounted thereon; hinge projections extending rearwardly from the door and arranged to engage the frame, each hinge projection having an extension in which is a socket; two posts located near the hinged portions of the door; and a coil spring on each post, one end of the coil spring being secured to the post and the other end of each coil spring located in the socket of the extension of the hinge projection of the door.

30. 3. The combination in a door frame, of a door having rearwardly extending hinge projections arranged to rock on the door frame, each projection having a socket therein; a bar located back of the frame of the range between the two hinge projections of the door; a post at each end of the bar; a coil spring on the post, the free end of the spring extending into the sockets of the projections, the said frame having a lug, and the bar having a projecting portion; and a screw-bolt extending through openings in the lug and in the projecting portion of the bar and securing the posts together.

45. 4. The combination in a range, of a frame; a door having hinge projections arranged to engage the frame, each projection having a socket; a fixed post near each hinge projection; and a coiled spring on each post, the free end of the coiled spring being bent at the outer end and arranged to rest in the 50 socket of the hinged extension of the door so that when the door is in the opened position additional friction will be placed upon the door.

60. 5. The combination in a frame of a range; of a door having hinge projections adapted

to rock on the frame; an extension projecting inwardly from the hinge projections; a detachable bar located on the inner side of the frame between the hinge projections; means for securing the bar to the frame; a post on each end of the bar; and a coil spring on each post, one end of each coil spring engaging its post and the other end of each coil spring engaging the extensions of the hinge projections of the door.
